JOHN A. CHURCH, JR., OF NEW YORK, N. Y., ASSIGNOR TO UNITED VERDE EXTENSION MINING COMPANY, OF NEW YORK, N. Y., A CORPORATION OF DELAWARE.

SMELTING FURNACE AND THE METHOD OF SMELTING ORES THEREIN.

Application filed June 9, 1925. Serial No. 35,902.

To all whom it may concern:

Be it known that I, JOHN A. CHURCH, Jr., a citizen of the United States, and resident of the borough of Manhattan, in the city and State of New York, have invented a new and useful Improvement in Smelting Furnaces and the Method of Smelting Ores Therein, of which the following is a specification.

10 The object of this invention is to provide novel means and method of feeding ores into a reverberatory furnace whereby a more rapid and effective smelting of the ores as well as a great economy in fuel is obtained 15 by depositing the ores on the floor of the furnace to produce gradually widening valleys for the flow of the molten material from the firing end toward the flue end of the furnace, thereby preventing the obstruction 20 of the flue or the pocketing of the molten material, said gradually widening valleys in the present instance being produced by forming a continuous longitudinal mound of gradually decreasing height from 25 the firing end toward the flue end of the furnace.

A further object is to provide means for feeding the ores into the furnace substantially continuously so that the continuous longitudinal mound will be maintained during the smelting operation and thereby the most effective and economical smelting of the ores may be obtained.

In the accompanying drawings:

25 Fig. 1 represents a reverberatory furnace in horizontal section with the improvements incorporated therein.

Fig. 2 represents a longitudinal vertical section through the furnace, taken in the plane of the line II--II of Fig. 1, looking in the direction of the arrows.

Fig. 3 represents a transverse vertical section through the furnace, taken in the plane of the line III--III of Fig. 2, looking in the direction of the arrows.

Fig. 4 represents a similar section taken in the plane of the line IV--IV of Fig. 2, looking in the direction of the arrows.

The furnace floor is represented by 1, the arched roof by 2 and the unfettled side walls by 3, 4. This furnace may be provided at its firing end with the usual nozzles 5 for the introduction of the heating medium, and at its other end with the usual flue 6. In the present instance where a

single longitudinal mound of ore is to be formed and maintained on the floor of the furnace, the roof 2 is provided centrally with a longitudinal row of closely spaced passages 7, through which the ores are fed in from gated hoppers 8, communicating with a suitable feeding mechanism 9, in such a manner that a continuous longitudinal mound of gradually decreasing height is formed and maintained from the firing end 65 toward the flue end of the furnace with the apex of the mound spaced from the side walls 3 and 4 of the furnace, thereby producing gradually widening valleys for the free flow of the molten material from the 70 firing end toward the flue end of the furnace between the sloping sides of the mound and the side walls of the furnace. The mound of gradually decreasing height may be formed, in the present instance, by manipulating the gates 10 of the hoppers 8, by opening each gate or group of gates to a little greater extent than the preceding gate or group of gates beginning at the flue end 75 of the mound until the mound is formed, and thereafter opening all of the gates to about the same extent to maintain the mound at its gradually decreasing height from the firing end toward the flue end of the furnace.

It is intended that this feeding of the ores shall be substantially continuous so that the continuous longitudinal mound will be maintained at the proper heights to utilize the effect of the heating medium most economically and at the same time to present a very extended ore surface to the action of said heating medium. This substantially continuous feeding in of the ores, as distinguished from periodic feeding in, permits the ores to be submitted to the action of the heating medium at a time when the ores most readily absorb the heat of the heating medium.

If found necessary, a greater or lesser portion of each of the side walls may be made of non-corrosive material, such, for instance, as magnesite or chrome bricks 11 where the molten material comes into contact with said side walls.

What I claim is:

1. The method of smelting ores in reverberatory furnaces which consists in feeding the ores into the furnace chamber in such a manner as to produce gradually widening

valleys for the free flow of the molten material from the fire end toward the flue end of the furnace, and subjecting the ores to the action of a heating medium.

6. In a reverberatory furnace which consists in substantially continuously feeding the ores into the furnace chamber in such a manner as to produce and maintain gradually widening valleys for the free flow of the molten material from the fire end toward the flue end of the furnace, and subjecting the ores to the action of a heating medium.

7. The method of handling ores in reverberatory furnaces which consists in feeding the ores into the furnace chamber in such a manner as to form a continuous longitudinal mound of gradually decreasing height from the fire end toward the flue end of the furnace to produce gradually widening valleys for the free flow of the molten material, and subjecting the mound to the action of a heating medium.

8. The method of handling ores in reverberatory furnaces which consists in substantially continuously feeding the ores into the furnace chamber in such a manner as to form and maintain a continuous longitudinal mound of gradually decreasing height from the fire end toward the flue end of the furnace to produce gradually widening valleys for the free flow of the molten material, and subjecting the mound to the action of a heating medium.

9. In a reverberatory furnace, means for feeding the ores into the furnace chamber to produce gradually widening valleys for the free flow of the molten material from the fire end toward the flue end of the furnace, and means for subjecting the ores to the action of a heating medium.

10. In a reverberatory furnace, means for substantially continuously feeding the ores into the furnace chamber to produce and subject gradually widening valleys for the free flow of the molten material from the fire end toward the flue end of the furnace, and means for subjecting the ores to the action of a heating medium.

11. In a reverberatory furnace, means for feeding the ores into the furnace chamber to form a continuous longitudinal mound of gradually decreasing height from the fire end toward the flue end of the furnace to produce gradually widening valleys for the free flow of the molten material, and means for subjecting the mound to the action of a heating medium.

12. In a reverberatory furnace, means for substantially continuously feeding the ores into the furnace chamber to form and maintain

65 a continuous longitudinal mound of gradually decreasing height from the fire end toward the flue end of the furnace and thereby produce gradually widening valleys 65 for the free flow of the molten material, and means for subjecting the mound to the action of a heating medium.

9. In a reverberatory furnace, means for feeding the ores into the furnace chamber 70 to form a continuous longitudinal mound of gradually decreasing height from the fire end toward the flue end of the furnace with the apex of the mound spaced from and its sloping sides leading to the side walls 75 of the furnace chamber to produce gradually widening valleys for the free flow of the molten material along the said side walls, the portions of said side walls which come in contact with the molten material being 80 formed of a non-corrosive material, and means for subjecting the mound to the action of a heating medium.

10. A reverberatory furnace having unfettled side walls, means for feeding the 85 ores into the furnace chamber to form a continuous longitudinal mound of gradually decreasing height from the fire end toward the flue end of the furnace to produce gradually widening valleys for the free flow of 90 the molten material, and means for subjecting the mound to the action of a heating medium.

11. A reverberatory furnace having unfettled side walls, means for feeding the 95 ores into the furnace chamber to form a continuous longitudinal mound of gradually decreasing height from the fire end toward the flue end of the furnace with the apex of the mound spaced from the side walls to 100 produce gradually widening valleys along the side walls for the free flow of the molten material, and means for subjecting the mound to the action of a heating medium.

12. A reverberatory furnace having unfettled side walls, means for feeding the ores into the furnace chamber to form a continuous longitudinal mound of gradually decreasing height from the fire end toward the flue end of the furnace with the 110 apex of the mound spaced from the side walls to produce gradually widening valleys along the side walls for the free flow of the molten material, and means for subjecting the mound to the action of a heating medium. 115 The portions of the said side walls which are exposed to the molten material being of a non-corrosive material.

In testimony, that I claim the foregoing as my invention, I have signed my name this 120 5th day of June 1927.

JOHN A. CHURCH, JR.
